OIL WELL PUMP AND THE LIKE

Roy L. Chenault, Oil City, Pa., assignor to Gulf Research & Development Company, Pittsburgh, Pa., a corporation of Delaware

Application March 20, 1944, Serial No. 527,285

6 Claims. (Cl. 103—240)

This invention relates to oil well pumps and the like, having a displacement chamber submerged in a pool of oil in a well which is alternately filled with oil from the pool and with gas under pressure from the top of the well, the oil in the chamber being displaced by the gas into well tubing for delivery to the surface of the ground.

Such pumps generally include two, spaced, concentrically arranged strings of tubing located in the usual casing of the well. The inner string forms an oil eduction pipe through which oil from the displacement chamber is conducted to the top of the well while the annular space between the tubes serves as a conduit to deliver gas under pressure from the top of the well to the chamber in the well. The flow of gas and oil is controlled and directed by means of valves carried by the tubing in the well for alternately establishing and interrupting communication between the annular gas space and the displacement chamber and then, for exhausting the displacement chamber of entrapped gas, between the displacement chamber and the well casing.

Heretofore difficulty has been encountered with pumps of this type in the design of an efficient yet simply constructed and operated arrangement of valves and tubing by means of which full and positive control of the pump is obtained even under adverse conditions of operation.

Piston, sleeve and poppet or plug-type valves have been used in these pumps but have not proven altogether satisfactory because of excessive wear and leakage, exaggerated occasionally by excessive quantities of sand in the oil, misalignment of the pump, etc. Proper seating of poppet and plug-type valves may not always occur if the pump is not perfectly vertical. Also, as is known in the art, when pumps of the above type are first installed in a well, or when such pumps are left idle in a well, sometimes for even a few hours, it may be difficult or impossible to start them. This is for the reason that oil accumulates in the well and may, under formation pressure, seek a level in both the well and the pump which is considerably in excess of the normal, working, submergence head of the pump. Then, since the oil in the pump is trapped by the action of the automatically closing oil inlet valve of the pump, compressed gas admitted to the pump for operating it must not only raise the already abnormal head of oil in the eduction tube, but must also operate against an additional head of oil occasioned by displacement of the contents of the annulus into the eduction tube. This additional head of oil may result in a three-

fold increase in head as when the inner and outer pump tubes are of one and two-inch diameter, respectively, and may require for lifting purposes, a gas pressure far in excess of the pressure of the gas available for normal, continuous pump operation.

When this occurs it is necessary to "unload" the pump, i. e., reduce the head of oil in the tubing to normal or to a weight of oil that can be raised by the pressure of the gas available for operating the pump. Generally this is accomplished through the provision of automatic "kick-off" valves at spaced intervals on the inner tube string. These valves automatically admit pressure gas into the inner tube string at progressively lower levels but their use is not always convenient, economical or satisfactory. Sometimes it may be desirable to completely evacuate the pump of oil into the well, as before "pulling" the pump or in advance of operation or to clear the pump of undesirable or foreign matter.

It is an object of the present invention to provide a pump of the character described, with an arrangement of valves and tubing such that proper seating of the valves is achieved even under adverse conditions of operation and though the tubing may deviate slightly from the vertical.

A further object of the invention is the provision of a pump of the character described which does not need kick-off valves and which may be quickly brought into operation regardless of the head of oil accumulating in the tubing above the displacement chamber.

A further object of the invention is the provision of valve means for discharging oil which accumulates in the annular gas space above the displacement chamber, directly into the well, that is, into the space in the well between the well casing and the pump.

A further object of the invention is the provision of means for discharging oil accumulating in the displacement chamber and inner tube string, as well as the oil accumulating in the annulus into the well, advantageously through the stand valve at the lower end of the displacement chamber, whereby both the tube strings of the pump and the displacement chamber may be entirely emptied of oil while the pump remains in position in the well.

A still further object of the invention is the provision of ball and seat valves in a pump of the character described for alternately connecting the displacement chamber with the gas supply and then with the casing, the valve assembly having a flow channel therethrough for discharg-

ing oil from the displacement chamber into the inner or eduction tube string for removing the oil from the well.

These and other objects are accomplished by the pump of the present invention as will be apparent from the following description and accompanying drawings wherein,

Fig. 1 is a view partly in vertical section and partly in elevation of the pump of the present invention.

Fig. 2 is a detail vertical sectional view of a portion of the pump showing one form of valve and valve actuating arrangement.

Fig. 3 is a detail vertical sectional view of the lower end of the pump including a portion of the displacement chamber.

Fig. 4 is a horizontal sectional view taken along line 4-4 of Fig. 2 in the direction of the arrows.

Fig. 5 is a horizontal sectional view taken along line 5-5 of Fig. 2 in the direction of the arrows.

Fig. 6 is a detail vertical sectional view taken along line 6-6 of Fig. 5 in the direction of the arrows, and

Fig. 7 is a detail vertical sectional view of a modified form of pump valve actuating cam.

Referring to the drawings wherein like numerals indicate corresponding parts throughout the several views, the complete pump assembly is shown in Fig. 1 and consists of an outer stationary string of tubing 1 and a reciprocating inner string of tubing 2, the two tube strings being spaced from each other and advantageously concentrically arranged. The outer string of tubing carries at its lower end a valve assembly or valve chest represented generally by the numeral 3, which in turn has attached to its lower end the upper end of a displacement chamber 4. The lower end of the displacement chamber is threaded internally and externally for connection respectively with the upper end of a working barrel 5 and, through coupling 6, with the usual pump screen 7, as shown.

The valve chest assembly consists of a thick walled, elongated, cylindrical body portion 8 (Figs. 2, 4 and 5), recessed and threaded at its upper end where it engages with coupling 9 for attachment to the end of the outer tube string, and threaded at its lower end for engagement with coupling 10 for connection with the upper end of the displacement chamber. The body portion of the valve assembly is provided centrally with a longitudinally disposed bore or working barrel 11 parallel to which and disposed adjacent thereto in the wall of the body portion about the central bore, are a plurality of smaller bores or tubular fluid passageways 12. Passageways 12 are advantageously equally spaced from each other and arranged with their longitudinal centers nearer to the wall of the central bore than to the outside wall of the body portion. The upper ends of passageways 12 are enlarged or countersunk, as shown at 13, to communicate with central bore 11 through narrow rectangular openings 14 and to receive valve balls 15 which are adapted to seat on short tubular extensions or valve seats 16 threaded into the ends of the passageways at the bottoms of each countersink. In this position as illustrated in Fig. 4, balls 15 close the ends of the passageways and project into bore 11 in a position to be moved by a cam adapted for reciprocation in the bore as described hereinafter, it being noted that when the valves are closed sufficient clearance space is provided between the balls and the outermost side walls of the countersunk portions to enable the cam to cock the balls

on their seats thereby opening the valves and affording communication between the passages and the interior of the countersunk portions.

Balls 15 being of larger diameter than the width 5 of the openings 14, are constrained from lateral displacement out of the countersunk portions through such openings and are further constrained from upwardly escaping by means of spider 17 which is suitably positioned in recess 10 18 of coupling 9. Spider 17 is provided with a center bore of equal or greater diameter than bore 11 and concentrically arranged with respect thereto, as shown.

Coupling 10 (Figs. 2, 5 and 6) is recessed as at 19 to receive the lower end of the valve assembly body portion and has a bore 20 equal to and concentric with bore 11. Surrounding bore 20 are small longitudinal bores or fluid passages 21 which terminate in communication with the ends of laterally disposed bores or passages 22. Passages 22 communicate through the side wall of the coupling with the outside of the pump, as shown. The upper ends of passageways 21 are countersunk and provided with ball valves 23, the structure, disposition and operation of which are substantially identical with the ball valve and seat arrangements in the valve assembly body portion just described. In addition, coupling 10 is provided with a plurality of longitudinal, open fluid passageways 24 (Figs. 5 and 6) advantageously spaced midway between passages 21. Passages 24 provide for uninterrupted communication between the displacement chamber and passages 12 in the body portion. In this regard it should be noted that, as shown, the recess in the top end of the body portion and the recess in the top end of coupling 10 are sufficiently deep to provide open fluid spaces or chambers 25 and 26, respectively, between the ends of the body portion and the adjacent ends of the coupling members.

As recited, the lower end of coupling 10 has connected to it, in screw threaded engagement, the top end of displacement chamber 4 which supports at its lower end pump working barrel 5. Barrel 5 has a bore 27 in axial alignment with bore 11 and of the same or less diameter. The lower end of barrel 5 is in threaded, adjustable engagement with a spider-like plug 28 which is provided with cylindrical openings 29 uniformly disposed about a centrally located pin 30 that projects into the barrel, as shown. The plug and the pin are secured in adjusted position on the end of this barrel by means of lock-nut 31.

Inner tube string 2 consists of a plurality of strings of pipe coupled end to end and extending down within the outer tube string to a point adjacent the valve assembly just described. Here it connects with a tubular cam-shaped member 32 of slightly less diameter than the diameter of bore 11. The lower end of cam 32 is tapered externally as at 33 to engage balls 15 when the tube string is lowered and cause them to ride up onto the cam and assume a position in which they are cocked off their seats to open the ends of passages 12. Internally, the lower end of cam 32 is threaded as at 34 to engage and support the upper end of a piston packing, carrying tube 35 which extends through working barrel 11. Tube 35 is reduced in outside diameter from a point 36 at which a shoulder is formed, downwardly to the end of the tube where it is threaded externally as at 37. Slid over the reduced end of tube 35 to lie against shoulder 36 are alternately, piston packing collars 38 and piston pack-

ing washers 39, the latter being formed of leather, fabric, rubber or metal or the like, and the collars and washers constituting the working piston in barrel 11. These piston elements are clamped tightly in position on tube 35 through spacer 40 by a lower cam member 41 which is threaded internally on its lower end for engagement with the end of tube 35. Externally, the lower end of cam 41 is tapered as at 42 to actuate balls 23 when the tube string is lowered, in the same manner as cam 32 actuates balls 15. In this connection it should be noted that cams 32 and 41 are in spaced relation on the tube string, such that at no time do cams 32 and 41 hold balls 15 and 23 off their seats simultaneously. Instead, considering the tubes positioned as shown in Fig. 2, in which the inner tube string is shown in raised position, cam 41 moves below and out of engagement with balls 23 when the inner string is lowered before cam 32 engages with balls 15 to move them off their seats.

Attached to the lower end of tube 35 by means of coupling 43 is a pipe 44 which extends into the displacement chamber 4 and is joined in turn by means of coupling 45 with a second piston carrying tube 46. Tube 46 extends down into working barrel 5 where it is provided with lateral, slotted openings 47 immediately below which the tube is reduced in diameter to form a shoulder 48 and a short extension 49 threaded at its lower end. Clamped against shoulder 48 by means of ball valve housing 50 is a second piston consisting of packing material 51 and spacing collar 52 which piston is adapted for sliding sealing engagement in barrel 5. Valve housing 50, formed as shown, has an inwardly extending annular flange 53 against which ball valve seat 54 is held by means of nipple 55. Ball 56 in housing 50 operates as a check valve to prevent the fluid which enters the displacement chamber and inner tube string through the valve from returning to the well when gas pressure is applied to the displacement chamber. For the purpose of emptying the contents of the displacement chamber and inner tube string into the well, however, the inner tube string is moved to its extreme lowermost position, at which time pin 30 on plug 28 engages with ball 56 through the valve and lifts it off its seat.

If desired, one or more ball check valves 57 may be inserted at different levels in the inner tube string as shown in Fig. 1, for preventing back flow of fluid down the inner tube string. With such valves in the line, a plurality of slugs of fluid may be raised in the tube simultaneously instead of completely removing one slug before the displacement chamber can be evacuated of pressure gas and allowed to fill again.

When positioned in a well, the outer tube string may be supported in concentric relation to the eduction tube by attachment through a T pipe coupling 58 to a projection or packing gland 59 of a lift cylinder of usual construction, a fragment only of which is shown at 60. Connected to the T is a pipe 61 for delivering pressure gas from any suitable source to the pump. The inner tube string is, of course, supported in the well and adapted to be raised and lowered to actuate the valves by attachment with the piston of the lift cylinder.

In operation of the embodiment of the invention just described, the outer tube string which carries the pump cylinders and valve assembly is lowered into position in the well and the inner tube string, or eduction tube which carries the piston and valve operating cams is next lowered

5 within the outer tube string to a position in which cam 32 holds balls 15 off their seats. In this position cam 41 will have passed below balls 23 permitting them to close the ends of passages 21. Considering then that during the time of installing the pump and connecting it for operation the level of liquid in the well has risen under formation pressure to an excessive height, liquid will enter the pump through screen 1 and ball check valve 56 into the displacement chamber through openings 47 and pass upwardly in the inner tube string to a height approximately equal to the standing level of liquid in the well. Under such conditions, gas admitted to the pump through pipe 61 will pass downwardly in the annular space between the tube strings and force the liquid therein through passages 12, space 26 and passages 24 into the displacement chamber from whence it will be forced through openings 47 into the eduction tube. However, when the weight of the column of oil in the eduction tube becomes equal to the pressure of the gas, flow of liquid into the tube will cease and liquid will not be ejected from the pump. Should this occur, it is simply necessary to lower the inner tube string until pin 30 lifts ball 56 off its seat at which time the liquid in the pump will be forced by the gas back into the well through the lower end of the eduction tube.

25 The inner tube string may be left in this lowest position until all of the oil in the pump is evacuated into the well or if desired it may be raised to normal, lowered position to permit ball 56 to seat when it is determined that the head of oil remaining in the pump can be raised by the pressure of the gas available to operate the pump. In normal lowered position, ball check valve 56 being closed and balls 15 being unseated by cam 32, pressure gas, stopped by piston packing 39 in barrel 11 passes downwardly through passages 12, space 26 and passages 24 to force liquid in the displacement chamber down and into the eduction tube through openings 47 and then up past check valve 57 to the top of the well. Upon exhaustion of liquid from the displacement chamber as recited, the eduction tube is raised to normal upper position, cam 32 releases balls 15 which immediately close the ends of passages 12, thus shutting off the flow of gas to the displacement chamber, and cam 41 comes into engagement with balls 23 to lift the same from their seats and permit the gas remaining in the displacement chamber to escape into the well through passages 24, space 26 and passages 21 and 22. As the displacement chamber is thus relieved of pressure gas, liquid in the well enters the pump as before but immediately as it is determined that the displacement chamber is filled, inner tube 2 is lowered to normal lower position and the liquid expelled as before recited.

70 In event it is not necessary or desirable to completely evacuate the pump of liquid into the well before beginning regular pumping, the modified form of apparatus shown in Fig. 7 may be used. Referring to Fig. 7, a cam 62 is provided on tube 35 in place of the lowermost piston packing, spacing collar 38 (shown in Fig. 2). This cam is adapted to unseat balls 23 upon lowering of the eduction tube beyond its normal, working, lower position. In this form of the invention pin 30 may be dispensed with so that only the liquid in the annular spaces and passages above ball valves 23 is expelled from the pump into the casing when the inner tube string is lowered to its extreme lowermost position. With this arrange-

ment liquid is **not** accidentally or unnecessarily expelled from the displacement chamber of the pump in initially evacuating the pump of excess liquid prior to regular pumping operation.

The pump of the present invention is simple in construction and operation and relatively inexpensive to manufacture and repair.

This application is a continuation-in-part of my application Serial No. 380,043, filed February 21, 1941.

What I claim is:

1. Apparatus for pneumatically pumping liquids from wells which comprises an inlet for gaseous fluid under pressure, a displacement chamber adapted to be positioned in the liquid in a well, ball check valve means for venting the chamber of entrapped gas to the well, a second ball check valve means for controlling the delivery of gaseous fluid from said inlet to said chamber, a vertically reciprocable eduction tube in communication with the lower part of said chamber and extending therefrom to the top of the well, and cam means carried by said eduction tube for operating said valves in accordance with the reciprocation of the tube, whereby when the tube is lowered gaseous fluid is admitted to the displacement chamber and when the tube is raised the displacement chamber is vented to the well.

2. The subject matter of claim 1 wherein the lower end of the displacement chamber is provided with an extension for receiving the lower end of the eduction tube, a valve adjacent the lower end of the eduction tube, said tube being provided with openings in its side walls in communication with the lower end of the displacement chamber above the valve and means carried by said displacement chamber extension for opening the valve when the eduction tube is lowered to an extreme lower operating position.

3. An apparatus for pneumatically lifting liquids from wells comprising inner and outer strings of tubing adapted to be positioned in a well, a displacement chamber carried by said outer string of tubing adjacent the lower end thereof, said inner string of tubing forming an eduction tube for delivering liquids from the chamber to the top of the well, a valve chest carried by said outer string of tubing, an exhaust passage leading from the chest to the outside of the outer string of tubing, a gas inlet passage for admitting gas under pressure to the chest, valve ports and valve port sealing means carried in said chest for controlling fluid flow through said exhaust and inlet passages, an open fluid passageway leading from

the displacement chamber to the chest and means separate from said valve port sealing means and carried by the eduction tube adapted upon reciprocation to actuate said valve port sealing means for alternately admitting pressure gas into the chamber to displace liquid therefrom into the eduction tube for delivery to the top of the well and then exhausting spent pressure gas from said chamber into the well.

4. The subject matter of claim 3 wherein said valves are ball check valves.

5. Apparatus for pneumatically pumping liquids from wells comprising spaced inner and outer strings of tubing adapted to be positioned in a well, said inner string of tubing forming an eduction tube, a displacement chamber carried by the outer tube string adjacent the lower end thereof, piston working barrels carried by said outer tube string above and below said displacement chamber, a valved fluid by-pass around said upper working barrel for establishing fluid communication between the displacement chamber and the space between the tubes above the working barrel, a valved passage extending from the top of the displacement chamber through the outside wall of the outer tube string, ball check valve means in said passage, pistons carried by the eduction tube in position for sliding, sealing engagement with the walls of the piston working barrels, said bottom piston and barrel closing off the lower end of the displacement chamber, ball check valve means adjacent the end of the eduction tube below the chamber, said tube being in open communication above said ball check valve with the bottom of said chamber, cam means above the piston in the upper working barrel and carried by the eduction tube for operating the valve in the by-pass, a second cam means below the piston in the upper working barrel and carried by the eduction tube for operating the valve in the passage extending from the top of the displacement chamber through the outside wall of the outer tube string, and means carried by the lower working barrel for opening the ball check valve in the end of the eduction tube when the tube is lowered to an extreme lower working position.

6. The subject matter of claim 1 wherein additional cam means is provided on the eduction tube for opening both of said valves simultaneously when the eduction tube is lowered to an extreme lowermost operating position.

ROY L. CHENAULT.
